W. L. LYNCH:
DRILL BRACE.
APPLICATION FILED SEPT. 19, 1918.

1,323,705.

Patented Dec. 2, 1919.

Inventor
William Leslie Lynch

Attorney.

UNITED STATES PATENT OFFICE.

WILLIAM LESLIE LYNCH, OF BROOKLYN, NEW YORK, ASSIGNOR TO TIMOTHY H. LYNCH,
OF BROOKLYN, NEW YORK.

DRILL-BRACE.

1,323,705.

Specification of Letters Patent.

Patented Dec. 2, 1919.

Application filed September 19, 1918. Serial No. 254,729.

To all whom it may concern:

Be it known that I, WILLIAM LESLIE LYNCH, a citizen of the United States, residing at Brooklyn, in the county of Kings, 5 State of New York, have invented certain new and useful Improvements in Drill Braces, of which the following is a full, clear, and exact specification.

This invention relates to drill braces or 10 rests, and has for its object to provide a device of this kind adapted to be used in a multiplicity of places or positions, whereby a single brace or rest will answer where several different ones have heretofore been 15 required.

A special object is to provide a drill brace capable of use for drilling any one or all of the three faces of a channel bar without changing the position of said bar. Another 20 object is to allow for drilling a plurality of holes in an arc without changing the bar-engaging portion of the brace with respect to the bar. Other objects will appear as the description proceeds.

25 The invention will be first hereinafter described in connection with the accompanying drawings, which constitute part of this specification, and then more specifically defined in the claims at the end of the description.

In the accompanying drawings, wherein similar reference characters are used to designate corresponding parts throughout the several views:—

35 Figure 1 is a side elevation of a drill brace constructed substantially in accordance with this invention applied to an angle or channel bar for holding a drill in position to work on one wing of said bar.

40 Fig. 2 is a similar view of the brace applied to the angle or channel bar for holding the drill in position to work on the other wing of the bar.

Fig. 3 is a similar view of the brace applied to the channel bar for holding the drill in position to work on the base or body portion of said bar.

Fig. 4 is a section on the line IV—IV of Fig. 3, and

50 Figs. 5 and 6 are detailed perspective views of modified forms of drill braces.

The preferred form of brace, as illustrated in Figs. 1 to 4, inclusive, comprises a piece of rigid metal of any suitable width 55 and thickness having a shank portion 1 and

an angularly bent and twisted arm or abutment portion 2 disposed at right angles to the longitudinal axis of the shank portion and to one side of said shank. The free end of the shank is bent at right angles and rebent to form the hook 3, and to the outer face of said hook there is swiveled a supplemental hook 4 by means of the rivet 5.

The supplemental hook 4 preferably disposed to face in the opposite direction from the hook 3, as best illustrated in Fig. 4, so that the hook 4 may be engaged with one wing 6 of a channel bar 7, as illustrated in Fig. 1, when the drill 70 is to be used on that wing, while the hook 3 may be engaged with the other wing 8 of said bar, as shown in Fig. 2, when it is to be drilled. When the hook 4 is in engagement with the bar, the shank and arm of the brace may be turned on the rivet 5 so as to permit the drill to be 70 adjusted for drilling holes at different points in the wing of the bar, either in an arc or otherwise, without changing the position of said hook 4 with respect to the bar.

Another supplemental hook, hereinafter 80 termed the longitudinal hook as distinguished from the transverse hooks 3 and 4, is illustrated at 9 swiveled to the side of the shank 1 of the brace by means of a pivot pin 10. Said longitudinal hook 9 may be engaged with either one of the wings of the channel bar, as illustrated in Figs. 3 and 4, for supporting the drill in position to work on the base or body portion 11 of the bar. The hook 9 may be adjusted at different 85 points along the shank of the brace to adapt it for use with various sizes of drills and channel bars. As illustrated in Figs. 1, 2, 3 and 4 of the drawings, this adjustment may be accomplished by engaging the pivot pin 90 10 with any one of a plurality of holes 12 in the shank, or with an elongated slot 13 in said shank. The pivot pin is retained in the selected hole or at the desired point along the slot 13 by means of a nut 14 screwed on the threaded outer end portion of said pin. 95

100 It will be observed that the preferred form of brace which has been described is of the universal type inasmuch as it is adapted to be used in a number of different places or positions. In Figs. 5 and 6 simpler forms of braces are illustrated for use on one wing of an angle or channel bar. The shank 15 of the brace shown in Fig. 5 has the angularly bent abutment arm 16 at one end and 110

at the other end a short bent portion 17 to which a hook 18 is swiveled, so that the shank and abutment arm may be turned on said swivel pin 19 for boring holes at different points without changing the position of said hook. In Fig. 6 the hook 20 is integral with the shank 21, as is also the abutment arm 22, this form of brace being the simplest but not having the swivel adjustment of the other forms.

Having thus described my invention, what I claim as new and desire to secure by Letters Patent of the United States is:—

1. A drill brace having a shank, an abutment arm arranged at an angle thereto at one end of the shank, an angularly bent portion at the other end of the shank, and a

U-shaped hook having one of its arms arranged flat against and swiveled to said angularly bent portion so as to extend transversely of the shank. 20

2. A drill brace having a shank, an abutment arm arranged at an angle thereto at one end of the shank, an integral U-shaped hook formed on the other end of the shank 25 and extending transversely thereof, and a separate U-shaped hook having one of its arms arranged flat against and swiveled to the outer arm of the integral hook so to also extend transversely of the shank. 30

In testimony whereof I have signed my name to this specification.

WILLIAM LESLIE LYNCH.
